UNITED STATES PATENT OFFICE.

HARRY SHOEMAKER, OF JERSEY CITY, NEW JERSEY.

RECEIVING APPARATUS.

1,009,106.

Specification of Letters Patent. Patented Nov. 21, 1911.

Application filed November 8, 1909. Serial No. 525,894.

To all whom it may concern:

Be it known that I, HARRY SHOEMAKER, a citizen of the United States, residing at Jersey City, county of Hudson, State of New Jersey, have invented certain new and useful Improvements in Receiving Apparatus, of which the following is a specification.

My invention relates to telegraphic or 10 telephonic receiving apparatus, and more particularly to the receiving apparatus employed in wireless telegraph or telephone systems in which the signals or messages are represented by electro-radiant energy 15 transmitted through the natural media.

My invention relates more particularly to receiving apparatus which shall be selective of the energy transmitted to it and which is provided with guarding means or apparatus for rendering it indifferent to or immune from other energy simultaneously transmitted.

To this end I provide means for rendering the receiving apparatus proper selective to a greater or less degree, and associate with such receiving apparatus means which shall be selective, to a greater or less degree, of other energy or energies which may be transmitted simultaneously with 20 the energy intended to be received by the receiving apparatus proper, and causing or allowing such other undesired energy or energies to be absorbed in paths or circuits other than the path or circuit including or 25 associated with the receiving apparatus proper.

The undesired energy which may be simultaneously transmitted with the energy representing the signal or message which 30 it is desired to receive, may be dissipated in a guard path or circuit to which it is selected to produce heat or to be otherwise consumed or transformed. To this end I may, for example, provide in such path or circuit 35 a resistance which shall consume the undesired energy and transform the same into heat.

For the purpose of consuming or converting the undesired energy, I may use in place 40 of a resistance any other suitable consumption or translating device.

My invention resides in other features hereinafter described and claimed.

My invention resides also in the method 45 of and apparatus for selectively receiving signals or messages as hereinafter described.

For an illustration of some of the forms which my improved receiving apparatus may take, reference is to be had to the accompanying drawings, in which:

Figure 1 is a diagrammatic view illustrating receiving apparatus proper with which is associated, by the employment of a separate and distinct aerial receiving conductor, a guard circuit or path for diverting and consuming the energy of an undesired signal or message. Fig. 2 is a diagrammatic view illustrating apparatus and means similar to that shown in Fig. 1, except that the aerial conductor is common to the receiving apparatus proper and to the guarding apparatus, the receiving and guarding apparatus being conductively connected with the aerial receiving conductor. Fig. 3 is a diagrammatic view of receiving 75 and guarding apparatus both inductively associated with a common aerial conductor. Fig. 4 is a diagrammatic view of a receiving apparatus inductively associated with an aerial conductor with which is inductively related a plurality of guard paths or circuits. Fig. 5 is a diagrammatic view illustrating the employment of a looped aerial conductor, a plurality of guarding paths or circuits being inductively related 80 with the loop while the receiver circuit proper is conductively associated therewith. Fig. 6 is a diagrammatic view of apparatus similar to that shown in Fig. 5, except that the receiving apparatus proper is 85 also in inductive relation with the looped aerial conductor.

In Fig. 1, A represents the receiving antenna or aerial conductor of a wireless telegraph or telephone station. Between the 95 conductor A and earth G are serially connected the inductance L and the variable condenser K, having preferably an air dielectric. The inductance L may take the form of a coil of wire wound upon a 100 cylinder of insulating material, or may take any other suitable form. As shown, a variable portion of this inductance L is connected in series with the aerial conductor A and the condenser K. In shunt to the variable portion L' of the inductance L is connected the variable condenser K'. In shunt to the condenser K' are connected the variable condenser K² and the detector or wave-responsive device D, of any suitable 110 type. And in shunt to the detector D is connected a circuit including the telephone.

instrument or other signal translating instrument T, it being understood that such local circuit will include a battery or other source of energy when the type of wave-
 5 responsive device or detector D requires it. By varying L and K, or either of them, the antenna circuit or path may have its natural period changed or varied between the limits for which it is suited or designed. By vary-
 10 ing L' and K' or either of them, the local or closed oscillating circuit may have its natural period varied to correspond with the natural period of the antenna path or circuit. The mutual inductance of the an-
 15 tenna circuit and the circuit including L' and K' may be varied, as by keeping L constant, but shifting its two contacts so as to change its geometrical relation with L'. The condenser K² is given such a value or
 20 adjusted to such a value that current flows through the receiver circuit only when L' and K' are adjusted for resonance.

The apparatus as thus far described constitutes a tuned or selective wireless tele-
 25 graph or telephone receiving system. It is to be understood that my invention is not limited to the receiving apparatus proper being constructed of the parts and arranged as shown, for it is readily understood that
 30 any other form or arrangement of selective receiving apparatus is comprehended by my invention.

Associated with the receiving apparatus proper, as above described, is the guarding apparatus for diverting from the receiving apparatus proper undesired energy which may be transmitted simultaneously with the energy which it is desired to interpret as signals or messages by the receiving appa-
 35 ratus proper. This guarding apparatus comprises the antenna or aerial conductor A' between which and the earth G is serially connected a variable inductance L', a variable resistance R and the variable condenser K'. The condenser K' may be short circuited by closing the switch s. When the switch s is open the condenser K' is in series in the antenna circuit or path and the effect is of inserting capacity in such path or cir-
 40 cuit so that the natural period thereof shall be less than the natural period of the circuit or path when the capacity is not so inserted, as when the switch s is closed. Since this guarding circuit or path includes re-
 45 sistance as R, such path or circuit has a greater dampening factor than the receiving apparatus proper, shown to the right of Fig. 1; that is to say, the undesired energy received in the guarding circuit or path is
 50 converted into heat by dissipation in the resistance R. L' and K', or either of them, may be adjusted so as to make the guarding circuit or path more or less selective of the undesired energy. The inductance L'
 55 may be of high resistance conductor so that

a separate resistance R need not be em-
 60 ployed.

Suppose two transmitting stations are si-
 65 multaneously sending out energy, the wave
 70 length of the one transmitting station which is communicating with the station at which the receiving apparatus of Fig. 1 is located, being λ , while the wave length transmitted by the other station is λ' . The receiving appa-
 75 ratus proper is then attuned to a wave length λ , while the guarding apparatus is at-
 80 tune to the undesired frequency, that is, to a wave length λ' . The energy having wave
 85 length λ will be received by the guard appa-
 90 ratus and dissipated into heat, or otherwise consumed or converted; at any rate, it is pre-
 95 vented from affecting or controlling the receiving apparatus proper. On the other hand, the energy having wave length λ will be received by the receiving apparatus proper and will do useful work in affecting, actuating or controlling the wave-responsive device or detector D, to reproduce signals or messages in the manner well understood in the art.

The resistance R of the guard circuit or path should be of such magnitude or value as to make the guard circuit or path prac-
 95 tically dead-beat, that is, the resistance should not be so great as to destroy entirely its oscillating properties, but should prefer-
 100 ably be high enough to convert all of the en-
 105 ergy of the oscillations corresponding to the wave length λ' as quickly as possible into heat. This preferred condition exists when the resistance R is equal to the

$$\sqrt{\frac{4L'}{K'}}$$

where L' is the inductance and K' repre-
 105 sents the effective capacity.

In Fig. 1 separate and distinct antennæ or aerial conductors A and A' are provided for the receiving apparatus proper and for the guard apparatus. In such case the dis-
 110 tance between the antennæ or aerial conductors A and A' should not be more than one-quarter of the length of the wave of the energy against which it is desired to guard the receiving apparatus proper, so that the receiving apparatus proper and the guard apparatus shall not operate as separate and independent receiving appa-
 115 ratus with regard to the received energy. While in Fig. 1 only one guard circuit or path is shown, several guard circuits may be employed if desired.

Thus, Fig. 2 represents a guarded receiv-
 120 ing apparatus with two guard circuits or paths, each suited for dissipating an unde-
 125 sired energy of given frequency or wave length. The arrangement is the same as in Fig. 1, except that now the same antenna is used for the guard apparatus as for the receiving apparatus proper. The second

guard circuit or path contains the variable inductance L^2 , an adjustable resistance R^2 and the variable condenser K^2 , which may be short circuited by the closure of the 5 switch s^2 . The path including the inductance L^2 may be attuned to an undesired frequency either above or below the frequency of the energy desired to be received by the receiving apparatus proper. And similarly, 10 the guard path including the inductance L' may be attuned to a frequency either below or above the desired frequency. It is to be understood that more guard circuits may be associated, than shown in Fig. 2, and at- 15 tuned to still other frequencies. With these guard circuits or paths any energy represented by frequencies above or below the frequency of the desired energy, is converted into heat and does not affect the receiving 20 apparatus proper.

In Fig. 3 are serially connected between the aerial conductor A and earth G the variable inductance L and the variable condenser K. Here, the receiving apparatus proper comprises the circuit inductively related to the antenna path or circuit and including the variable inductance L' , variable condenser K' , etc. And the guard circuit or path is also inductively related with respect to the antenna circuit or path and includes the variable inductance L' , variable condenser K' and variable resistance R. It is preferred that the guard circuit including the resistance R should be closely coupled 5 or in close inductive relation with the antenna circuit or path, while the receiver circuit proper may be loosely coupled with the antenna circuit or path.

In Fig. 4 the arrangement is similar to that shown in Fig. 3, except that a plurality of guard circuits are inductively related with the antenna circuit or path. Here again, it is preferred that the guard circuits be closely coupled with respect to the antenna circuit or path, while the receiving circuit proper may be loosely coupled with the antenna circuit or path. These three guard circuits or paths are easily distinguished as including respectively the variable resistances R' , R^2 , and R^3 , variable inductances L' , L^2 , and L^3 , and variable condensers K' , K^2 , and K^3 . These guard circuits are attuned to the frequencies of the undesired energies.

In Fig. 5 the aerial conductor A is in the form of a loop, the loop being completed by a variable inductance L, a connection being made to earth G through the condenser K from a variable point along the inductance L. In shunt to a variable portion of the inductance L is connected the variable condenser K' , in shunt with which is a variable condenser K^2 and the detector D, as in the previous cases the detector D and the telephone or signal translating instrument T

belonging to the receiving apparatus proper. Here two guard circuits are shown in inductive relation with the loop circuit or path. One of these guard circuits includes the variable inductance L' , adjustable resistance R' and variable condenser K' . The other comprises the variable inductance L^2 , adjustable resistance R^2 and the adjustable condenser K^2 . Obviously, only one of these guard circuits may be employed or a greater 70 number than shown may be employed and attuned for the purposes hereinbefore described. 75

Fig. 6 is similar to Fig. 5, except that the receiving apparatus proper is inductively related with respect to the loop path or circuit instead of conductively as in Fig. 5. Here again, more or less guard circuits than shown may be employed for the purposes above indicated. Here again, the guard 85 circuits are preferably closely coupled with respect to the loop circuit while the receiving apparatus proper may be loosely coupled. And it is to be understood that whenever inductive couplings are employed the 90 coupling may be made either loose or close.

What I claim is:

1. The combination with receiving apparatus, of guarding apparatus associated therewith, said guarding apparatus comprising means for selecting energy of the frequency of undesired energy, and means in said guarding apparatus for dissipating the selected energy and preventing sustained oscillations. 95

2. The combination with receiving apparatus selective of energy of desired frequency, of associated guarding apparatus selective of undesired energy of a different frequency, and means in said guarding apparatus for dissipating the received undesired energy and preventing sustained oscillations. 105

3. The combination with apparatus for receiving high frequency electro-radiant energy, of guarding apparatus therefor comprising means for selecting energy of undesired frequency, and a resistance sufficient to prevent persistent oscillations in said selecting means. 110

4. The combination with receiving apparatus, of guarding apparatus comprising means for selecting energy of undesired frequency, and a dissipative resistance, said dissipative resistance being of a value for rendering said guard apparatus almost dead-beat. 120

5. The combination with a selective receiving apparatus, of a plurality of associated guarding apparatus, each guarding apparatus diverting from said receiving apparatus energy of undesired frequency, each guarding apparatus being selective of energy of a frequency different from the frequency of which every other is selective, and 125 130

means associated with each guarding apparatus for dissipating the energy selected thereby and for preventing persistent oscillations.

5. 6. The combination with receiving apparatus, of guarding apparatus associated therewith, said guarding apparatus comprising a closed circuit selective of energy of undesired frequency, and means in said 10 closed circuit preventing persistent oscillations.

7. The combination with a selective receiving apparatus, of guarding apparatus associated therewith, said guarding apparatus comprising a closed circuit selective 15 of energy of undesired frequency, and means in said closed circuit giving to said circuit a dampening factor greater than the dampening factor of said receiving apparatus.

20. 8. In combination, receiving apparatus comprising a tuned path, and associated guarding apparatus comprising a tuned path having a greater dampening factor than said first mentioned tuned path.

25. 9. In combination, receiving apparatus, comprising a path tuned to energy of desired frequency, associated guarding apparatus comprising a path tuned to energy of undesired frequency, the tuned path of the 30 guarding apparatus having a greater dampening factor than the tuned path of said receiving apparatus.

10. In combination, an aerial conductor, and a receiving circuit associated therewith, 35 means for tuning said receiving circuit to desired energy, an associated antenna, and means tuned to a different frequency associated therewith.

11. In combination, an aerial conductor, 40 and a receiving circuit associated therewith, means for tuning said receiving circuit to desired energy, an associated antenna, and means tuned to a different frequency associated therewith and including energy dissipating means.

45. 12. In combination, an aerial conductor, and a receiving circuit associated therewith, means for tuning said receiving circuit to desired energy, and a second aerial conductor, and tuning means having a greater dampening factor than the receiving apparatus associated with said second aerial conductor.

13. In combination, an aerial conductor, receiving apparatus associated therewith, 5 means for tuning said receiving apparatus to a desired frequency, and a guarding path in inductive relation with respect to said antenna and tuned to a different frequency, said guarding path including energy dissipating means preventing sustained oscillations.

14. The combination with an antenna, of receiving apparatus associated therewith, means for tuning said receiving apparatus to 6 desired frequency, and a plurality of guarding paths in inductive relation with said antenna, each guarding path tuned to a different frequency, and each having a greater dampening factor than said receiving apparatus.

15. The combination with a looped aerial conductor, of receiving apparatus associated therewith, means for tuning said receiving apparatus to energy of desired frequency, and a guard path associated with said looped aerial conductor and tuned to a different frequency, the dampening factor of said guard path being greater than that of the receiving apparatus.

16. The combination with a looped aerial conductor, of receiving apparatus associated therewith, means for tuning said receiving apparatus to energy of desired frequency, and a guard path associated with said looped aerial conductor and tuned to a different frequency, the dampening factor of said guard path being greater than that of the receiving apparatus, said guard path including a dissipative resistance.

In testimony whereof I have hereunto affixed my signature in the presence of the two subscribing witnesses.

HARRY SHOEMAKER.
